UNITED STATES PATENT OFFICE.

GEORGE H. BENEDICT, OF NEW YORK, N. Y.

DESIGN FOR A PACKAGE-HOLDER.

SPECIFICATION forming part of Design No. 15,736, dated January 20, 1885.

Application filed October 6, 1884. Term of patent 7 years.

To all whom it may concern:

Be it known that I, GEORGE H. BENEDICT, of the city, county, and State of New York, have invented a new and original Design for 5 a Package-Holder; and I do hereby declare that the following is a full and exact description thereof, reference being had to the accompanying drawing, and to the letters of reference marked thereon, making a part of 10 this specification.

My invention relates to the configuration of a package-holder.

It consists in the configuration of the outer arm of the hook, which has the form of a 15 double curve, the outer end of said curved arm being bent inward to approach more or less closely the main stem or arm of the hook.

A B A B in the accompanying drawing represent the hooks of a package-holder, C. The 20 main stem or inner arm, A, of each hook is straight, or nearly so, as in the ordinary form of hooks. The configuration of its outer arm, B, from the point *m* to the point *n* is, as shown in the drawing, that of a double curve, or sub- 25 stantially in the shape of a letter S, the cen-

tral portion, *r*, being straight or but slightly curved. The connecting-bend between the outer and inner arms of the hook is in the general form of a semicircle, and the outer arm inclines inward, so that its upper curve 30 shall approximate more or less closely the inner arm at *i*.

The ornamentation of the device may be heightened by extending the curve at the outer extremity of the arm, so that it shall 35 close, or nearly so, upon the main length of the arm in the form of an eye, *w*.

I claim as my invention—

The design for a package-holder herein shown and described, the same consisting of 40 hooks A B at the ends of a cylindrical handle, C, each hook having a double curve, *m n*, and a terminal inner bend, *w*, in its outer arm.

In testimony whereof I have signed my name to this specification in the presence of two sub- 45 scribing witnesses.

GEORGE H. BENEDICT.

Witnesses:

G. H. SPENCER,
JOHN A. ELLIS.
